CLAIM

The ornamental design for scoreboard in the form of an emblem, as shown and described.

DESCRIPTION

FIG. 1 is a front elevational view of a scoreboard in the form of an emblem showing our new design;

FIG. 2 is a side elevational view thereof;

FIG. 3 is a top plan view thereof;

FIG. 4 is a bottom plan view thereof; and,

FIG. 5 is front elevational view of second embodiment of FIG. 1.

The side, top and bottom views of the second embodiment are the same as disclosed in FIGS. 2-4 of the first embodiment respectively.
